CLAIM

I claim the ornamental design for a lead-free airgun pellet, as shown and described.

DESCRIPTION

FIG. 1 is a top perspective view of a first embodiment of a lead-free airgun pellet of the present invention;

FIG. 2 is front view thereof, wherein the rear view, right side view, and left side view are all mirror images thereof;

FIG. 3 is a top view thereof, wherein the bottom view is a mirror image thereof;

FIG. 4 is a top perspective view of a second embodiment of a lead-free airgun pellet of the present invention;

FIG. 5 is front view thereof, wherein the rear view, right side view, and left side view are all mirror images thereof;

FIG. 6 is a bottom view thereof; and,

FIG. 7 is a top view thereof.

The ornamental design which is claimed is shown in solid lines in the drawings. Any broken lines in the drawings are for illustrative purposes only and form no part of the claimed design.
